UNITED STATES PATENT OFFICE.

LILLIAN A. STRASBURGER, OF NEW YORK, N. Y.

ORNAMENTAL WORK SIMILAR TO LACE OR DRAWN WORK.

1,333,687.

Specification of Letters Patent. Patented Mar. 16, 1920.

Application filed February 21, 1919. Serial No. 278,532.

To all whom it may concern:

Be it known that I, LILLIAN A. STRASBURGER, a citizen of the United States, residing in the borough of Manhattan, city of New York, county of New York, and State of New York, have invented a new and useful Improvement in Ornamental Work, Similar to Lace or Drawn Work, of which the following is a specification.

10 The object of the invention is to provide an attractive and durable form of ornamental work, serviceable for various of the uses of lace or drawn-work or the like, and possessing numerous novel characteristics 15 and capabilities. It constitutes in effect a rigid, or semi-rigid, ornamental open-work, suitable for panels of various descriptions, for lamp-shades and for the construction of many other articles and elements of design. 20 The product comprises an open wire net, that is to say a net substantially rigid as compared with a thread net for example, and a design of thread, cord or yarn, of wool, cotton, silk or other material, colored 25 or uncolored, embroidered or wound in and out of the meshes of the net. The manner of disposing or leading the thread may be widely varied, it being possible either to simulate various kinds of lace or needlework, 30 or to produce effects distinctly novel in their character. In one form of the invention beads are combined as an element of the fabric. Beautiful and unique results can be produced in this way, for lamp-shades and 35 other transparencies, as well as other purposes, through the use, particularly, of combinations of different colored threads or yarn and beads also of different colors.

In the accompanying drawings, forming 40 a part hereof:

Figure 1 is a face view of an illustrative flat panel having a number of designs worked therein;

Fig. 2 is an enlarged fragmentary face 45 view;

Fig. 3 is a section corresponding to Fig. 2;

Fig. 4 is a side elevation of a lamp-shade embodying the form of the invention with beads;

Fig. 5 is a plan view of Fig. 4; and 50
Fig. 6 is an enlarged sectional detail of this form.

Fig. 1 shows an open wire net 1, bound by a frame 2. The net is substantially rigid, or firm, though of course it may be 55 bendable, and in Figs. 4 and 5, in fact, the frame 2^a is shown curved to cylindrical form.

Upon the net one or more designs are formed by passing thread 3 in and out 60 through the meshes, back and forth, and in various directions. In the central illustrative design 4, practically all the courses or stitches are in one direction, horizontal. In the two corner designs 4^a both vertical and 65 horizontal stitches or threads, woven upon themselves, are used. In the other corner design 4^b curved or whirled threads are used in addition. At the upper left an interlocked circular ground pattern 4^c is 70 shown. Elements such as 4^d can be built up independently of the net and tacked thereto.

The lamp-shade of Figs. 4-6 is made with a tubular net 1^a with end rings 2^a; and an interior frame 5 to rest upon an electric 75 bulb. The design or pattern is here produced with thread or yarn 3^a and beads 6, the beads being strung upon the thread at intervals. The beads are somewhat smaller 80 than the openings of the net, and are located therein, each bead being successively bordered by passes of the thread and by the rectangle formed by the intersecting strands of the net. In this way a jeweled effect is obtained, which is especially striking in 85 transmitted light. Numerous other combinations of the net, thread and beads can, of course, be produced.

In both of the illustrated forms, it will be observed, the width of the meshes of the 90 net is much greater than the thickness of the thread, the net forming an open skeleton, which is both a firm support and an element of the ornamentation.

What is claimed as new is:

1. An ornamental metal and thread fabric 95 comprising an open wire net with stitches embroidered in design through the meshes.

2. Ornamental work comprising the combination of an open wire net, and a design of thread and beads embroidered thereon.
3. Ornamental work comprising the combination with a substantially rigid net, of threads embroidered upon said net, and beads upon the threads located within the meshes of the net.
4. Ornamental work comprising an open substantially rigid net with threads em-
10

broidered in design through the meshes, the width of the meshes of the net being much greater than the thickness of the thread.

5. Ornamental work comprising an open substantially rigid net with threads em- 15
broidered in design through the meshes and beads upon the threads within the meshes, the individual beads being bordered by thread within the meshes.

LILLIAN A. STRASBURGER.
